UNITED STATES PATENT OFFICE.

EDWARD SOULÉ, OF BROOKLYN, NEW YORK.

DESIGN FOR A DIRECTION-SIGNAL CASING.

Application filed January 9, 1923. Serial No. 4,838. Term of patent 14 years.

To all whom it may concern:

Be it known that I, EDWARD SOULÉ, a citizen of the United States, residing in the city of New York, borough of Brooklyn, in the county of Kings and State of New York, have invented a new, original, and ornamental Design for Direction-Signal Casings, of which the following is a specification, reference being had to the ac-

companying drawings, forming a part thereof, and of which—

Figure 1 is a perspective view and Fig. 2 is a side elevation of a direction signal casing showing my new design.

I claim:

The ornamental design for a direction signal casing, substantially as shown.

EDWARD SOULÉ.
